OF BEVERLY, MASSACHUSETTS.

METHOD OF FORMING CHAIN-STITCH SEAMS.

1,030,815.

Specification of Letters Patent. Patented June 25, 1912.

Application filed August 28, 1909. Serial No. 515,059.

To all whom it may concern:

Be it known that I, CHARLES P. HOLMES, a citizen of the United States, residing at Lynn, in the county of Essex and State of Massachusetts, have invented certain new and useful Improvements in Methods of Forming Chain-Stitch Seams; and I do hereby declare the following to be a full, clear, and exact description of the invention, such as will enable others skilled in the art to which it appertains to make and use the same.

The present invention relates to an improved method of forming a chain stitch seam. The several steps of the improved method are such that they can readily be performed by suitable thread handling devices either embodied in a sewing machine and operated automatically or held in the hands of a workman and operated manually.

The manner in which the thread is manipulated in accordance with the present invention and the advantages secured thereby will be apparent to those skilled in the art from the following description taken in connection with the accompanying drawing in which the Figures 1 to 6 inclusive, illustrate somewhat diagrammatically a chain stitch seam formed by the method of the present invention connecting the insole, upper and welt of a shoe, and the preferred manner of performing the several steps of the method.

Referring to the drawings 1 indicates the insole, 2 the upper and 3 the welt of a shoe.

4 indicates the thread which is being manipulated in accordance with the preferred manner of practicing the present invention to form a chain stitch seam connecting the welt, upper and insole.

5 indicates a hooked or barbed needle and 6 a gripping device which may be conveniently employed in manipulating the thread.

Fig. 1 illustrates the positions of the needle, gripping device and thread, prior to the operation of exerting a stitch setting strain on the seam, Fig. 2, the positions after the stitch setting strain has been applied and Figs. 3, 4, 5 and 6, the positions during the steps of drawing a loop of thread

through the materials and through a previously formed loop and shortening the preceding loop. The steps constituting the method are taken in regular order and are 55 repeated until a seam having the desired number of stitches is completed. Any step may therefore be considered the first step of the method but for convenience of description the method may be considered as 60 beginning with the step of drawing a loop of thread through the materials and through a previously formed loop.

Starting with the parts in the positions illustrated in Fig. 2 in which figure the 65 needle is shown as through a previously formed loop and through the materials, with the previously formed loop drawn tight around the needle, a loop of thread, indicated at 7 in Fig. 3, is measured off on the 70 supply side of the work sufficient in length to form one side of the loop of thread drawn through the work by the needle. The thread is then laid in the hook of the needle and the needle is retracted, drawing a loop of 75 thread through the materials and through the previously formed loop as indicated in Fig. 4. Preferably the needle retracts a sufficient distance to draw the thread taut around the between substance 8 of the insole but without exerting any appreciable strain thereon sufficient to compress the between substance. The side 9 of the loop drawn up by the needle, which side leads to the preceding loop and may therefore be 80 called the work side, is now gripped by the gripping device 6, as indicated in Fig. 4, and the gripping device is retracted as indicated in Fig. 5 so as to exert a pull on the 85 work side of the loop in the general direction of the previously formed seam. At the same time preferably the supply end 1 of the thread is relieved of tension so that the supply side 11 of the loop drawn up by the needle offers no appreciable resistance to the 90 shortening of the preceding loop 12. The preceding loop 12 is thus shortened so that its end lies back of the last needle hole and during this shortening of the loop 12 no injurious strain is brought upon the thread, 95 the needle or the materials being sewed.

In the preferred manner of manipulating

the thread illustrated in the drawing, the work side of the loop leading from the gripper to the needle is wrapped around the needle as is clearly shown in Fig. 5 so that 5 there is no liability of the thread becoming disengaged from the barb of the needle. After the preceding loop 12 has been shortened to the desired extent, as above described, the work side of the loop drawn 10 out by the needle is released by the gripping device and the needle and work are given a relative movement to bring them into the position illustrated in Fig. 6. Then the needle is passed down through the loop 15 and through the materials at the point where the next loop is to be drawn. As the needle starts down toward the work, as indicated in dotted lines in Fig. 6, a pull is preferably exerted on the supply end 10 of the thread 20 so as to keep taut the loop extending around the needle and thereby prevent thread from being drawn back from the work side of the loop into the preceding loop when the supply end of the thread is pulled upon to 25 exert a stitch setting strain on the seam as hereinafter described. The needle and thread now have the relative positions indicated in Fig. 1, in which figure it will be seen that the last formed loop extends 30 around the needle 5 and passes through the previously formed loop. A pull is now exerted on the supply end 10 of the thread and the last formed loop is drawn tightly around the needle. By reason of the fact 35 that the previously formed loop is shorter than the distance between two needle holes, it is drawn forward as indicated in Fig. 2, the between substance, upper, and welt are tightly compressed without any injurious 40 reeving of the thread around the materials, the end of the preceding loop is drawn down onto the materials, and a stitch setting strain is exerted upon the seam.

It will be noted that the loop preceding 45 the loop drawn out by the needle is shortened accurately to the desired extent without exerting any injurious strain upon the needle, thread or materials, and that the materials are compressed and the stitches 50 of the seam drawn tight by the pull exerted on the supply end of the thread after substantially all of the slack thread has been removed from the loop preceding the loop drawn out by the needle. A tight seam can 55 thus be produced without the use of an excessive tension and without liability of injury to the materials. The seam will contain no loose thread and the loops of the chain will be drawn into such a position 60 that they will remain permanently in place.

While in the preceding description the step of shortening the preceding loop has been described as being performed by gripping and pulling upon the work side of the 65 needle loop, it is to be understood that this

step of the method broadly considered is not limited to this particular manner of operating upon the needle loop but contemplates acting on the needle loop in any suitable manner in the general direction of the previously formed seam to shorten the preceding loop. It is also to be understood that the step of acting on the needle loop while the supply end of the thread is relieved of tension to shorten the preceding 70 loop constitutes a feature of the invention which may be used in connection with means other than those hereinbefore described for exerting a stitch setting strain on the seam. 75

The nature and scope of the invention having been indicated and the preferred manner of practicing the invention having been described, what is claimed is:—

1. That improvement in the art of forming a chain stitch seam which consists in drawing a loop of thread through the materials to be sewed and through a previously formed loop, acting on the last formed loop in the general direction of the previously formed seam while the supply end of the thread is relieved of tension to shorten the preceding loop back of the point at which the last loop was drawn through the material, and thereafter pulling the preceding loop forward to exert a stitch setting strain 90 on the seam. 95

2. That improvement in the art of forming a chain stitch seam which consists in drawing a loop of thread through the materials to be sewed and through a previously formed loop, acting on the last formed loop in the general direction of the previously formed seam while the supply end of the thread is relieved of tension to shorten the preceding loop, inserting an instrument 100 through the last formed loop and through the materials at the point where the next loop is to be drawn, and pulling on the supply end of the thread to draw the last formed loop tightly around the instrument 105 and exert a stitch setting strain on the seam. 110

3. That improvement in the art of forming a chain stitch, seam which consists in drawing a loop of thread through the materials to be sewed and through a previously 115 formed loop, gripping the work side of the last formed loop and exerting a pull thereon in the general direction of the previously formed seam to shorten the preceding loop, inserting an instrument through the last formed loop and through the materials at the point where the next loop is to be drawn, and pulling on the supply end of the thread to draw the last formed loop tightly around the instrument and exert a stitch setting 120 strain on the seam. 125

4. That improvement in the art of forming a chain stitch seam which consists in drawing a loop of thread through the materials to be sewed and through a previously 130

formed loop, gripping the work side of the last formed loop and pulling thereon in the general direction of the previously formed seam while the supply end of the thread is relieved of tension to shorten the preceding loop back of the point at which the last loop was drawn through the material, and

thereafter pulling the preceding loop forward to exert a stitch setting strain on the seam.

CHARLES P. HOLMES.
